INFRARED RAY EQUIPMENT

Ralph W. Lashells, Findlay, Ohio

Application March 27, 1946, Serial No. 657,396

2 Claims. (Cl. 219—34.1)

1

This invention relates to infrared ray equipment and particularly to that type thereof in which infrared ray lamps are arranged in banks so as to direct the rays therefrom upon an object to be treated thereby, the principal object being the provision of a construction including a minimum number of standard parts so constructed and arranged as to permit banks of infrared lamps of various sizes and shapes to be constructed therefrom at a minimum of expense.

Objects of the invention include the provision of a construction of mounting a plurality of infrared ray lamps in banks including parts which may be cut to length, and/or employed in multiple, to produce a bank of infrared ray lamps of any desired size and shape; the provision of a construction as above described in which the infrared ray lamps are arranged in rows and each row has a single reflector associated therewith common to all of the lamps of such row; the provision of a construction as above described in which the framework of a bank includes end frame assemblies of standard section interconnected by cross members which are formed to provide conduits for the wiring employed for energizing the lamps; the provision of a construction as above described including certain standard parts and/or sections capable of being used in the construction of a bank of infrared ray lamps regardless of the size or shape of the bank; and the provision of a construction as above described that is simple in construction, efficient in operation and economical to manufacture.

The above being among the objects of the present invention, the same consists in certain novel features of construction and combinations of parts to be hereinafter described in reference to the accompanying drawings, and then claimed, having the above and other objects in view.

In the accompanying drawings which illustrate suitable embodiments of the present invention and in which like numerals refer to like parts throughout the several different views,

Fig. 1 is an end view of two banks of infrared ray lamps constructed in accordance with the present invention and arranged in opposed relation with respect to each other whereby to form an oven-like structure through which articles to be heated thereby may be passed.

Fig. 2 is a rear quarter perspective view of one of the banks of infrared ray lamps shown in Fig. 1 to better bring out the construction thereof.

2

Fig. 3 is a fragmentary perspective view illustrating a modified form of construction for a part of the structure shown in Fig. 2;

Fig. 4 is an enlarged, partially broken, perspective view, taken looking in the same direction as in Fig. 2 and showing one of the reflectors, the associated horizontal and vertical conduit forming members, and fragments of associated parts in exploded view.

Fig. 5 is a still further enlarged fragmentary, perspective view taken in the same direction as in Figs. 2 and 4 illustrating in greater detail the construction at the end of the horizontal conduits and the various attaching means therefor, and

Fig. 6 is an enlarged, transverse, sectional view taken upon the line 6—6 of Fig. 2 through one of the horizontal conduits and the associated reflector.

In infrared ray lamp equipment it is conventional practice to provide banks of infrared ray lamps each bank in the form of a unit including supporting means for a plurality of infrared ray lamps and reflectors associated therewith. The arrangement is that two such banks or units of lamps may be arranged in spaced but opposed relationship with respect to each other on opposite sides of the path of movement of work therebetween so as to form, in effect, an oven through which the work is passed to be heated by the infrared ray lamps in order to have some resulting effect, as for example, the drying of a coat of paint or enamel with which the work has been provided with.

It will, of course, be appreciated that various manufacturing plants produce articles of widely varying sizes and shapes which may desirably be processed by infrared ray lamps and that the banks of lamps in each case may vary in size and shape from those required or desired in other cases. If different parts are required for each different size and shape of the bank of infrared ray lamps required in each case, then it will be appreciated that the ultimate cost to the user will be higher than if this were not necessary, and the manufacturer of such banks of lamps will be required to carry a greater inventory of parts than if this were not the case. Accordingly, it is desirable in the manufacture of such banks of infrared ray lamps that each bank or unit be formed of standard parts adaptable for use in any unit regardless of the size or shape thereof, and standard structural or other sections which may come in relatively extended lengths so that all they require, in be-

ing adapted to banks or units of different sizes and shapes, is to be cut to the required length. The invention relates to the latter type of structure and, because of its design, it is believed to be particularly efficacious in producing infrared ray banks of lamps or units at a minimum of expense, it makes it possible for such banks or units to be quickly and readily fabricated, and it produces a highly efficient apparatus.

Referring now to the accompanying drawings, each bank of lamps constructed in accordance with the present invention includes a pair of laterally spaced end frames preferably formed from a standard structural section such, for instance, as the angle iron sections shown in the drawings. In the broader aspects of the invention, it will, of course, be appreciated that the method of supporting each bank of lamps is more or less unimportant, but it has been found desirable that such banks of lamps be mobile, and for that reason the end frames in the constructions shown are provided with caster wheels for movably supporting the same from a floor or other supporting surface.

The shapes of the end frames will, of course, vary with the desired cross-sectional shape of the bank formed in each case to conform to the size and shape of the particular object or class of objects which the banks of lamps are intended to treat. In the particular case illustrated in Fig. 1, it is assumed that the object to be heated is a relatively elongated object such as indicated at 10 in Fig. 1, of generally rectangular configuration and which, as a matter of illustration, may be treated by passing it between a pair of opposed banks of lamps such as illustrated in Fig. 1 as by means of a monorail conveyor indicated generally at 12. In the case shown in the drawings, it is assumed, by way of illustration, that the object 10 is of such size that each bank of lamps desirably include six rows of lamps so arranged so as to project the rays therefrom not only upon the sides of the member 10 but also upon the top and bottom surfaces thereof. Accordingly, this arrangement desirably includes the four center rows of lamps arranged to project the light therefrom laterally in a generally horizontal direction against the corresponding side of the object 10, and the upper and lower rows arranged to direct the light therefrom downwardly and inwardly, and upwardly and inwardly, respectively, so as to project the rays therefrom against the corresponding top and bottom surfaces of the object 10. With this in mind and appreciating that the framework to be described is arranged in this particular case to obtain this result, the modification of such framework to vary the arrangement of the various rows of lamps to conform them to any desired size or shape of object will be readily appreciated by those skilled in the art.

In adapting the present invention to the set of circumstances above pointed out, each end frame member of each bank comprises a vertically directed angle iron element 14 arranged with one flange thereof parallel to the general plane of the bank and the other flange thereof directed rearwardly from the outer edge of the first flange. The angle iron 14 at its lower end is rigidly fixed as by welding or the like to a relatively short horizontally directed angle iron 16 arranged with its length perpendicular to the general plane of the bank. The angle iron 16 is of identically the same section as the angle iron 14, and to each of its opposite ends is suit-

ably secured a caster wheel assembly indicated generally at 18. The angle iron 14 is substantially longer than the desired vertical spacing of the four rows of horizontally directed lamps to be employed, and adjacent its lower end an angle iron member 20 is extended between it, at a point spaced upwardly from its point of connection with the member 16, to the member 16 at a point spaced longitudinally thereof from its point of connection with the member 14, and the member 20 is suitably secured to both the members 14 and 16 in any suitable manner, as by welding or the like. It will be noted that the member 20 is arranged with its length perpendicular to the plane including the axes of the lower row of lamps, this being for a purpose which will hereinafter be described. Additionally, an angle iron member 22 is suitably secured, as by welding or the like, to the upper end of each member 14 and extends upwardly and inwardly therefrom and also perpendicular to the plane including the axes of the upper row of lamps. As will be appreciated, the members 20 and 22 are required only to accommodate corresponding rows of lamps which are directed at a different angle than the lamps arranged with their axes perpendicular to the plane of the front face of the members 14.

The above described simple structure is all that is necessary for each end frame and it will be understood that all elements thereof except the caster wheel assemblies 18 are formed from standard structural sections simply cut to length, and/or shaped where required, and welded or otherwise suitably secured together. In the particular case shown, all the members are shown as being formed from the same size and shape of structural elements, although this is not essential in the broader aspects of the invention even though desirable.

The end frames thus described are connected together in pairs by means of a plurality of interconnecting horizontally directed cross members 30, each centrally arranged with respect to a plane including the axes of a correspondingly desired row of lamps. As best brought out in Fig. 4, each member 30 is formed from sheet metal into a channel section, the open side of which is directed rearwardly. All of the members 30 are identical to each other in size, shape, and configuration, and are preferably simply cut from relatively long lengths of such section which may be kept in stock.

In order to secure the ends of the cross members 30 to the end frame members, each end of each cross member 30 is provided with a mounting bracket best brought out in Figs. 4 and 5. As brought out in Fig. 5, each mounting bracket comprises a rectangular plate 32 of the same size as the internal dimensions of a cross member 30, and is provided with laterally turned flanges 34 along the three edges thereof, all turned in the same direction from the plane of the plate 32. Along the fourth edge a laterally directed flange 36 is provided turned in the opposite direction from the flanges 34. The brackets at each end of each member 30 are identical to each other. These brackets are mounted in the ends of the cross members 30 in the manner illustrated in Figs. 4 and 5, that is, with the flanges 34 received within the channel of the members 30 with the plate 32 thereof flush with the corresponding end of the member 30 and with the flange 36 in the plane of the open side of the member 30 and directed away therefrom, and

they are suitably secured in place in any suitable manner, as by welding or the like. The flanges 36, at opposite ends of each member 30, overlie the forward face of the corresponding frame members 14, 20, or 22, as the case may be, and are suitably fixed thereto in any suitable manner as by screws, rivets, welding or the like.

The forward wall of each cross member 30 is provided with an opening 38 therein in line with the intended position of each lamp, and suitably secured within each cross member 30 in line with each of these openings 38 is a suitable or conventional lamp socket 40 adapted to receive the threaded end of a lamp, indicated at 42. Thus, the members 30 not only serve as cross members for the framework for each bank or unit, but also serve as receptacles for the sockets 40 and the wiring, a fragment of which is shown and indicated at 44 in Fig. 4, and also illustrated in Fig. 6.

In order to connect the wiring within each cross member 30 with that in each other cross member, each cross member 30, as best brought out in Fig. 4, intermediate its ends and preferably centrally thereof as shown, is provided with a short length of vertically directed channel 50 arranged with its open side facing rearwardly, the same as the channels 38. In fact, the channels 50 are preferably formed by cutting off corresponding lengths of the same stock from which the channel cross members 30 are formed from. The upper and lower walls of each cross member 30 are notched out to receive the corresponding channel 50 therein. In order to reinforce the cross members 30 at the point which they are notched to receive the corresponding channel member 50, a flanged plate member 52 is inserted between the upper and lower walls of each cross member 30 at each side of the notch provided therein for the channel member 50 and in flush relation with respect to the sides of the notch, and is suitably fixed thereto. Each plate member 52 is provided with an opening 54 therein aligned with a similar opening in the side wall 45 of the corresponding channel member 50 so as to permit the projection of the wiring 44 in each cross member 30 on either side of the corresponding channel 50 to within the corresponding channel 50. If desired, conventional nipples or bushings may be projected through these openings to prevent cutting of the wiring 44 by the sharp edges thereof as well as to serve as a means for securing each channel 50 to its corresponding cross member 30, or such securing may be effected in any other suitable manner. The channels 50 are, as brought out in Fig. 4, preferably provided with end members 56 suitably formed and fixed with respect thereto, such end members being provided with openings 58 for the passage of the wiring 44 therethrough.

As best brought out in Fig. 2, the channels 50 preferably project an equal amount above and below their corresponding cross members 30 and they are preferably of such length that when the cross members 30 are assembled in vertically spaced relationship to each other, as to the end frame members 14, their opposed ends abut each other as indicated, and in which case conventional bushings or nipples may be projected through the openings 58 of abutting ends 56 for the purpose of rigidly securing them together and for the purpose of protecting the wiring from the sharp edges of the openings 58. In the case of the upper and lower members 30 which are not

vertically aligned, the corresponding channel members 50 may be formed so as to extend into contacting relationship with respect to the next adjacent channel members 50 if desired, or, where the members 50 are all identical as shown, short angularly sectioned lengths of such channels may be interposed between the resulting spaced ends of the angularly disposed channels and the ends of the next adjacent channel. Preferably, however, and as brought out in Fig. 2, it is simpler and cheaper merely to extend the piece of flexible tubing 60 between an end of each such angularly disposed channel 50 and the adjacent end of the next adjacent channel 50, the opposite ends of the flexible tube 60 being conventionally secured in the corresponding openings 58 of the channels.

The open sides of the channel sectioned cross members 30 and the open sides of the channels 50 are preferably closed, and for that purpose each channel sectioned cross member 30 on each side of its corresponding cross channel 50 is provided with a channel sectioned cover 62 adapted to fit over the upper and lower walls of each member 30 and to close the open sides thereof, and they may be removably secured in place in any suitable manner as by screws 63. Similarly, each channel 50 is provided with a corresponding cover 64 which may be removably secured thereto in any suitable manner as by screws 65.

Thus, each cross member 30 and its cover 62 and each channel member 50 and its cover 64 form a closed conduit in which the wiring of the various lamps 42 is enclosed and protected and additionally the cross members 30 and their covers 62 form a receptacle or enclosure for the various sockets 40.

Instead of employing channel members such as 50 of the length shown in Fig. 2 and described in connection therewith, it may be desirable in some cases to make the channels 50 of the shorter length as for instance, illustrated at 50a in Fig. 3, with such channels being otherwise identical to those in Fig. 2. In the latter case when the various cross members 30 are assembled, then the opposed ends of adjacent channel 50a will be spaced from one another and in such case short lengths of flexible tubing 60a, of the same general character as the flexible tubing 60 previously described, may be employed to connect the opposed ends of adjacent channel members 50a, all as brought out in Fig. 3. The result is, of course, substantially the same in both cases although where the ends of the channels abut each other and are secured together as in the case illustrated in Fig. 2, it may aid in affording the structure some additional rigidity.

Now in banks of infrared ray lamps of the type described, it is desirable, and particularly so where the lamps employed are of the type devoid of self-contained reflecting surfaces, to provide some means for reflecting the rays from the lamps in properly diffused relation upon the work and preventing the rays from being projected in a direction which will have no utility. In the present case, the reflecting means employed consists of a trough-like member indicated generally at 70, one reflector 70 being provided for each row of lamps 42. Each reflector 70 is of a length equal to the distance between the end frames of the device and, as brought out in Fig. 6, each comprises a substantially flat inner wall 72 and a pair of opposite outwardly diverging substantially flat side walls 74, the latter preferably terminating at their free ends in

laterally outwardly directed flanges 76. Each inner wall 72 is provided with openings 78 therein in line with each lamp 42 and through which the stem of each lamp projects, and each reflector 70 is mounted with its central longitudinal plane including the axes of the lamps 42 for the corresponding row. Preferably, the side walls 74 are arranged in outwardly diverging relationship with respect to the central plane of the reflector and corresponding lamps 42 at an angle between 30° and 45° as by this arrangement certain advantages in the reflection of the rays from the lamps 42 is obtained, as brought out in detail in my copending application for Letters Patent of the United States on the same subject matter as the present application, filed on even date herewith, and serially numbered 657,395 now Patent Number 2,497,676.

Preferably, but not necessarily, the reflectors 70 are formed from relatively thin sheet aluminum having a specular finish providing a reflectivity of in the neighborhood of 80% or better, as such material has been found to be ideally suitable for use as such reflectors and, additionally, when formed from suitably thin sheets it is such as to permit the side walls 74 to be bent with respect to the inner wall 72, and the flanges 76 bent with respect to the side walls 74, to readily adapt them to varying spacing of the rows of lamps 42, to varying angular relationship between adjacent reflectors 70, and to meet other conditions as will be readily understood by those skilled in the art. It will be understood, however, that the reflectors 70 are preferably formed to a standard section and in relatively long lengths so that in building up a bank or unit all that is required is to cut such long lengths into the shorter lengths required in any particular installation and, if necessary, bend the side walls 74 with respect to the inner walls 72, and/or the flanges 76 with respect to the side walls 74, to accommodate them to the particular arrangement of parts being produced.

Preferably, the spacing of the rows of bulbs 42 is such that the adjacent flanges 76 of adjacent reflectors 70 overlap each other as brought out in Fig. 1 in which case the overlapping flanges 76 are preferably secured together as by sheet metal screws or the like indicated at 80. Where as in the case of the reflectors for the upper and lower rows of lamps 42 in the arrangement shown in Fig. 1 the angle of the inner side of the reflector is substantially the same as the flange 76 on the next adjacent reflector 70, then and as in the case shown the first flange may be simply removed if desired.

The reflectors 70 are mounted in the manner shown, each from its corresponding cross member 30, and this is accomplished by fixing to the upper and lower face of each cross member 30 at each end thereof a forwardly projecting sheet metal leg 82, the forward end of each of which is outwardly bent as indicated at 84 in Fig. 6, and lies in contacting relationship with respect to the inner wall 72 of the corresponding reflector 70 and is secured thereto as by means of screws 86. At the center of each member 30, or at least at the position in the length thereof at which the corresponding channel member 50 is located, a relatively wide leg 88 is fixed to each upper and lower face of the member 30. Each leg 88 is centrally notched, as brought out in Fig. 4, to fit around the corresponding channel 50, and the legs 88 thus serve to reinforce the channel 30 where it is cut out to receive the correspond-

ing channel 50. As in the case of the legs 82, the forward end portions of the legs 88 are laterally outwardly flanged as at 90 and are similarly secured to the rear walls 72 of the corresponding reflector 70. Thus, each reflector is mounted upon its corresponding channel 30.

The last described feature is desirable inasmuch as in building up a bank or unit of light the various channels 30 which are to be employed therein including all of the auxiliary associated parts may be built up as complete sub-assemblies and then applied as such to the end frames of the bank or unit. For instance, in such case and referring to Fig. 4, each such sub-assembly may comprise a channel member 30 and its corresponding channel member 50, the corresponding reflector 70 secured thereto by the corresponding legs 82 and 88, the corresponding mounting brackets 32 and brackets 52, covers 62 and 64, the various sockets 40 and the wiring therefor if desired. By this method of assembly, relatively small units are provided upon which the bulk of the work may be easily and quickly performed after which these sub-assemblies may be simply assembled together and to the end frames to produce the final product. It is important to note that the end frames including the members 14, 16, 20, and 22 all comprise suitable lengths of the same standard sectional material so that regardless of the size or shape of the bank of lamps to be constructed only one size of the standard structural element is required to be carried in stock and to be available. Likewise, the cross members 30 and channels 50 are all formed from the standard section so that regardless of the shape or size of the bank of lamps to be constructed, they may be formed by simply cutting off suitable lengths of such stock and properly forming such cut off lengths if and as required. The covers 62 and 64 are likewise formed from a standard section and may be provided by simply cutting off suitable lengths of stock of such section. The brackets 32 and 52 are of the standard size and may be employed regardless of the length of the bank of lamps to be constructed, and the legs 82 and 88 are standard in size and shape and the reflectors 70 are of a standard section. Accordingly, by employing a relatively small number of standard sections for the various elements of a bank of lamps constructed in accordance with the present invention, and the small number of standard brackets or the like, substantially any desired size and/or shape of infrared ray lamp bank or unit may be quickly and economically constructed and with the result that a highly efficient device is provided.

As previously mentioned, it is common practice to mount a pair of such banks or units of infrared ray lamps in opposed relation to each other as brought out in Fig. 1 so as to form, in effect, an infrared ray oven through which articles such as the article 10 may be passed by any suitable means as, for instance, the monorail conveyor 12 for treatment by the lamps. In such installations, because of the high degree of heat given off by the lamps, some arrangement is desirably provided for protecting the wiring for the lamps against the deleterious effect of such heat. Where such banks of lamps are constructed in accordance with the present invention then, as brought out in Fig. 1, the reflectors 70 serve to shield the conduits for the wiring, namely the cross members 30 and the channels 50, from direct reception of all except a minor portion of

the rays from the lamps 42. The cross members 30 and channels 50 are, however, spaced rearwardly from the reflectors 70 and are connected thereto only by the legs 82 and 88, which, being relatively narrow as compared to the length of the reflectors and being relatively thin, provide only relatively small and limited paths for the conduction of heat directly from the reflectors 70 to cross members 30 and channels 50. In other words, it may be said that the legs 82 and 88 form paths of low heat conductivity between the connected members so that the heat absorbed by the cross members 30 and channels 50 will be mainly absorbed by convection and/or radiation of heat from the reflectors 70. However, in view of the fact that the cross members and the channels 50 are spaced rearwardly from the reflectors 70, a free path is provided for the flow of air upwardly over the rear faces of the reflectors between the reflectors and the cross members 30, and over the cross members 30 and the channels 50. This provides an efficient means for carrying off the heat from the members forming the conduits for the wiring and consequently prevents these conduit forming members from reaching a temperature detrimental to the wiring contained therein. This last mentioned flow of air is indicated by the arrows 90 in Fig. 1.

Furthermore, in arranging a pair of such banks of lamps in opposed relationship, as illustrated in Fig. 1, the two banks will be arranged in opposed relation with the opposed edges of the upper and lower reflectors 70 in spaced relation with respect to each other as shown and as is necessary particularly where the work such as 10 is moved between the two banks by means of a conveying mechanism located above or below the same. This permits air to flow under and between the opposed lower reflectors 70, as indicated by the arrows 92 in Fig. 1, then upwardly between the two banks of lamps 42 and then escape from between the opposed edges of the two upper reflectors. This provides a natural draft of air upwardly between the banks which is particularly advantageous where the work being performed is the drying of a paint or enamel coating on an object, or the driving off of some volatile substance from the work, as in such case fresh air is continuously supplied which more readily absorbs and carries off such volatile substance.

Having thus described my invention, what I claim by Letters Patent is:

1. Infrared ray equipment comprising, in combination, a pair of laterally spaced and vertically directed end frame members, a plurality of vertically spaced horizontally extending cross members interconnecting said end frames, said cross members each comprising a channel sectioned member arranged with the open side thereof facing rearwardly, the forward wall of each of said cross members being provided with a plurality of laterally spaced openings therethrough, a plurality of lamp sockets within each of said cross members secured thereto one in line with each of said openings, wiring disposed in the channel of each of said cross members

interconnecting said sockets, vertically extending conduit means interconnecting said cross members including a plurality of relatively short channel sectioned members, each arranged with its open side facing rearwardly, the upper and lower walls of each of said cross members being notched out to receive one of said channel sectioned conduit members and each one of said cross members having one of said channel sectioned conduit forming members fixed with respect thereto, removable means closing the open sides of said cross members, removable means closing the open sides of said channel sectioned conduit means, a plurality of vertically and horizontally spaced legs fixed to each of said cross members and projecting forwardly therefrom, a generally trough shaped reflector of approximately the same length as said cross members arranged in forwardly spaced relation to each of said cross members, the reflector corresponding to each of said cross members being fixed to the forward terminus of said legs for the corresponding cross member and arranged with the channel thereof opening away from said cross member, and each of said reflectors having an opening in a rear wall thereof in line with each opening in the corresponding said cross members.

2. An assembly unit for infrared ray equipment comprising, in combination, an elongated channel sectioned member having a plurality of longitudinally spaced openings in the bottom wall of the channel, a plurality of lamp sockets fixed to said member within the channel, thereof, the side walls of said channel being notched out between the ends of said member, a relatively short channel sectioned element received in said notch with its open side opening in the same direction as the open side of said member and fixed thereto, said element projecting beyond opposite sides of said member, wiring in the channel of said member interconnecting said sockets, said wiring extending into said element, a trough shaped reflector of substantially the same length as said member arranged with the bottom of the trough in opposed, parallel and spaced relation to said bottom of said channel, said bottom of said trough having openings therein one aligned with each of said openings in said member, and means extending between and secured to said member and said reflector connecting them into a unitary structure.
